(57) **CLAIM**

The ornamental design for a shoe, as shown and described.

DESCRIPTION

FIG. 1 is a left side view of a shoe showing the claimed design;

FIG. 2 is a right side view thereof;

FIG. 3 is a front view thereof;

FIG. 4 is a rear view thereof;

FIG. 5 is a top view thereof;

FIG. 6 is a bottom view thereof;

FIG. 7 is a top perspective view thereof; and,

FIG. 8 is an enlarged view of a portion of the surface of the shoe shown in FIG. 2.

The even dashed broken lines in FIGS. 1-7 and the ghosted area(s) within the even dashed broken lines show portions of the shoe that form no part of the claimed design.

The dot-dashed broken line rectangle in FIG. 2 shows the limits of the enlarged view, FIG. 8, and forms no part of the claimed design.
